United States Patent Office

Des. 212,260
Patented Sept. 17, 1968

212,260

COFFEE MILL OR THE LIKE

Douglas N. Cabell, Bloomfield Hills, Mich., assignor to Ronson Corporation, Woodbridge, N.J., a corporation of New Jersey

Filed Dec. 26, 1967, Ser. No. 10,036

Term of patent 14 years

(Cl. D55—1)

Fig. 1.

Fig. 2.

Fig. 3.

FIG. 1 is a front perspective view of a coffee mill or like showing my new design.

FIG. 2 is a top view thereof.

FIG. 3 is a bottom view thereof.

FIG. 4 is a front view thereof.

FIG. 5 is an end view thereof.

FIG. 6 is a rear view thereof.

I claim:

The ornamental design for a coffee mill or the like, substantially as shown.
